UNITED STATES PATENT OFFICE.

JOHN F. BEAR, OF MANSFIELD, OHIO.

SUPPORTER FOR SUSPENDERS.

1,419,802.

Specification of Letters Patent. Patented June 13, 1922.

Application filed June 23, 1921. Serial No. 479,883.

To all whom it may concern:

Be it known that I, JOHN F. BEAR, a citizen of the United States, residing at Mansfield, in the county of Richland and State 5 of Ohio, have invented a new and useful Supporter for Suspenders, of which the following is a specification.

This invention relates to garment supporters, and more particularly to supporters 10 commonly known as suspenders.

The primary object of the invention is to provide novel means to insure movements of the suspenders with the body of the user to eliminate binding of the suspenders.

15 A further object of the invention is to provide means of this character of a construction to reduce the wear on the straps which connect the body portion of the suspenders to the trousers, to a minimum.

20 With the foregoing and other objects in view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

30 Referring to the drawing:—

Figure 1 is a fragmental plan view of suspenders disclosing a link constructed in accordance with the present invention, as 35 forming a part thereof.

Figure 2 is an elevational view of the link disclosing the rollers in section.

Figure 3 is a vertical sectional view 40 through the link.

Referring to the drawing in detail, the reference character 5 designates the main or shoulder straps of the suspenders which are provided with the usual connecting links 6 that connect the trousers straps to the shoulder straps 5.

The trousers straps in the present invention include an upper section 7 and a lower section 8, the upper section 7 including a pair of straps 9 which have their ends connected to the link members 6 as at 10, the

intermediate portions thereof operating over the rollers 11 and 12 which form a part of the link.

The link embodies a body portion 13 having a curved elongated opening 14 to accommodate the lower section 8, the opening 14 forming a bar 15 with the upper portion of the link, and as shown, the upper portion of the body is cut away to provide opposed arms 16 and 17, which arms are twisted or 60 formed at right angles to the side faces of the body portion to present relatively straight smooth strap engaging portions 18 to reduce wear directed to the edges of the strap to a minimum.

65 The arms 16 and 17 are provided with suitable openings to accommodate the bar 19, which bar is provided with right angled portions 20 forming arms, the extreme ends of the bar being bent into parallel relation 70 with the lower portion of the bar to provide a support for the roller 11.

From the foregoing it will be seen that due to the curvature of the opening 14, and the bar 15, the straps which engage the bar 75 15 and the walls of the opening 14 are supported so that the side edges thereof are normally out of contact with the ends of the opening as well as the arms 16 and 17.

Having thus described the invention, what 80 is claimed as new is:

In a suspender link, an upper section and a lower section, the upper section comprising opposed bars, rollers supported on the bars, the lower section comprising a bar 85 having a curved elongated opening, opposed arms forming a part of the lower section, said arms having openings to accommodate portions of one of the bars of the upper section to permit of pivotal movement between the sections, and said arms adapted to engage the ends of one of the rollers.

In testimony that I claim the foregoing as my own, I have hereto affixed my signature in the presence of two witnesses.

JOHN F. BEAR.

Witnesses:

CHAS. W. CONKLIN,
E. HAUTZEMAEDER.
